VICTOR L. FRYKMAN, OF BRIDGEPORT, CONNECTICUT, ASSIGNOR TO DICTAPHONE CORPORATION, OF BRIDGEPORT, CONNECTICUT, A CORPORATION OF NEW YORK

RECORD-RESURFACING MACHINE

Application filed September 3, 1927. Serial No. 217,337.

This invention relates to record-resurfacing machines, and more particularly to an improved machine for shaving record-blanks, particularly those intended for use with dictation machines.

Record-resurfacing machines as previously proposed have comprised a frame, a rotatable record-supporting mandrel mounted on the frame, a movable mandrel-end supporting means, a record-ejecting mechanism, and a tool-carriage adapted to be moved longitudinally of the frame over a record supported by the mandrel. This carriage, in the form shown, comprises means for quickly setting the record engaging tool relative to a record to be resurfaced and automatically operated means for advancing the tool step-by-step toward the record for successive finishing cuts.

A feature of the present invention is the provision of means for automatically ejecting the record incidental to the movement of the mandrel-end supporting means to inoperative position, so that the record will be ejected without attention on the part of the operator when the mandrel supporting means is moved preparatory to the removal of the record from the machine.

Another feature is the provision of means for automatically and coordinately releasing the knife-bar locking means, restoring the knife advancing means, and ejecting the record from the record-supporting mandrel incidental to the movement of the mandrel-end supporting means to inoperative position when a record has been resurfaced and is to be removed from the machine.

A further feature is the provision of means which automatically causes the return of the record-ejector to inoperative position after a record has been ejected and while the mandrel-end supporting means is inoperative to support the mandrel, so that the record-ejector is not in position to obstruct or prevent the final placing of another record on the mandrel while the mandrel-end supporting means is still in inoperative position.

Other features and advantages will herein-after appear.

50 In the accompanying drawings which illus-

trate one form of the present invention, that at present preferred—

Figure 1 is a top plan view of a record-resurfacing machine made in accordance with the present invention.

Fig. 2 is a rear view, partly in section, of a record-resurfacing machine made in accordance with the present invention, showing the movable mandrel-end supporting means in mandrel supporting position, with the related record ejector, knife-bar lock releasing and feed restoring means in normal or inoperative position.

Fig. 3 is a view similar to Fig. 2, but shows the end gate out of mandrel supporting position with the record-ejector in operative position and the knife-bar lock released and feed means restored, and shows the mechanism for accomplishing these various operations in position to trip-off and become temporarily disassociated from the means which it operates.

Fig. 4 is a fragmentary view, partly in section, of the interconnected knife-bar and gage in set position relative to a record.

Fig. 5 is a bottom skeleton plan view of some of the operating parts of the present invention.

Fig. 6 is a side sectional view showing the automatic step-by-step knife-advancing means.

The record-resurfacing machine illustrated herein comprises a base 12 provided with a left-hand standard 13 and a right-hand standard 14. Supported between these standards is a carriage guide rod 15 adapted to receive a bearing sleeve 16 of a knife-bar carriage 17. The knife-bar carriage 17 extends forwardly and upwardly from the sleeve 16 to a point near its forward end where it is provided with a ball-shaped weight and hand-piece 18 shaped to be conveniently grasped and to act as a hand-piece by means of which the carriage is moved, and from the latter it continues downwardly to a shoe portion 19 which normally contacts with and slides on a front rail 20 forming part of the frame.

Located in front of the guide rod 15 and supported at one end on a pivot screw 21 car-

ried by the standard 14, is a mandrel shaft 22 carrying a driving pulley 23 and a mandrel 24. At its end opposite the pulley 23, the mandrel shaft is supported for rotation by a pivot screw 25 carried by an end gate 26 secured to a shaft or stud 27 which is rotatably mounted in the frame 12 at 28. The end gate 26 is held in mandrel supporting position engaging the end of the front rail 20 by a self-locking manually releasable spring catch 29 engaging a cooperating stud 30. The catch 29 is provided at its front end with a finger piece 31 by means of which it is manipulated. When the gate 26 is opened by swinging it from the position shown in Fig. 2 to that shown in Fig. 3, the mandrel shaft 22 rests on an auxiliary support 32 on the frame 12, and free movement of the mandrel and mandrel shaft to the left, as viewed in Fig. 1, is prevented by a collar 33 carried by the mandrel shaft and adapted to engage the support 32.

The end-gate 26, in addition to supporting the free end of the mandrel, also functions to prevent the record from being thrown off the mandrel (which might cause serious damage) should the record accidentally become loosened from the mandrel or should the operator fail properly to place the record on the mandrel before starting the machine. In the broader aspects of the invention, therefore, the part 26 should be understood to be a mandrel-end guard.

After a record 34, which is to be resurfaced, is placed on the mandrel 24 as shown in Fig. 1, the operator grasps a handle portion 35 on the gate 26 and swings the latter on its shaft 27 until a pin 36 on the end gate enters an aperture 37 in the rail 20, while the pivot screw 25 in the end gate enters a companion hole 38 in the end of the mandrel shaft and raises the mandrel shaft to operating position. With this movement, the catch 29 engages the stud 30 and serves to hold the mandrel in operating position. This means for locking the end gate as illustrated and described is claimed in the patent to Thomas Herlihy, No. 1,726,894, patented September 3, 1929.

With the record mounted on the mandrel 20 and the end gate locked in mandrel supporting position, the record is in position to be shaved which results from movement of a knife 39 mounted on the carriage 17 longitudinally of the record 34 on the rod 15 and rail 20 under the influence of a rotating feed screw 40 mounted between the standards 13 and 14 and engaged by a feed nut 41 mounted on the sleeve 16 of the knife-bar carriage. The feed-screw 40 is caused to operate co-ordinately with the mandrel shaft 22 by means of a connecting belt 42 engaging a pulley 43 on the feed screw 40 and a pulley 44 carried by the mandrel shaft 22 along side of the pulley 23. The pulley 23 is usually driven

by an electric motor (not shown) mounted below the frame 12.

Phonograph record-blanks are customarily cut or shaved to resurface them for use when it is desired to obliterate an old record before making a new record on the surface of the blank. This operation may also be accomplished by means of burnishing, melting or other arrangements, and so far as some of the salient features of the present invention are concerned, it is immaterial whether the record-engaging tool used be a knife, a burrisher, or other device. However, since the method of cutting is the one most frequently used and most preferable at present, means for that purpose is illustrated herein.

Accordingly, the machine shown in the accompanying drawings comprises a knife-bar 45 adapted to carry at its forward end the knife 39 usually formed of sapphire or other hard stone. This knife-bar is slidably mounted in a housing or knife-carrier 46 which is pivotally mounted on the carriage 17 and is adapted to be moved so as to bring the knife 39 into contact with the record surface, so that simultaneous rotation of the record 34 and travel of the knife 39 with the knife-bar carriage 17 while the knife is in engagement with the record causes the top surface thereof to be removed. The knife is preferably provided with a chip-chute 47 into which the shavings from the record pass and through which they fall downwardly through a trough 48 forming part of the frame 12 to a suitable container below the frame provided for the purpose of receiving the chips.

In order that the knife 39 may be quickly and easily set to proper operating position for taking a first or preparatory cut when resurfacing a record-blank, means are provided whereby a direct manual operation, requiring no special attention on the part of the operator, causes the knife bar to be so set that it will extend into the record material only a predetermined and set amount, whereby the layer of record material removed will be of predetermined thickness. This means, comprises a gage-bar 49 mounted in the knife-bar carrier 46 for the knife-bar 45 and adapted to slide parallel therewith. The knife-bar 45 and gage-bar 49 are tied together by a yoke or tie-bar 50 for movement en bloc toward and from the record surface, so that, when they are moved forwardly toward the record blank, the front face 51 of the gage will engage the record surface and limit the extent of forward movement of the knife 39 beyond the record surface.

The knife-bar 45, the gage-bar 49 and yoke 50 are so interconnected and formed that the working surface of the knife 39 usually extends beyond the working surface 51 of the gage bar 49 by an amount equal to substantially fifteen thousandths of an inch. This, with an additional advance of five thou-

sandths of an inch obtained by means herein-after described, represents the depth of a first or preliminary cut.

It is sometimes desirable, however, to change the depth of cut determined by the gage 49, and this is accomplished by providing on the gage a screw-threaded portion 52, adjustable in the threaded section 53 of the tie-bar 50 connected to the knife bar 45.

10 These parts are locked in the adjusted position by a threaded disc 54 which preferably has a cup-section 54a which acts as a finger-piece by means of which the gage-bar and knife-bar are moved toward the record 34.

15 When the gage-bar has been set relative to the knife to suit average conditions, these parts are moved from normal inoperative position to position for taking a first or preparatory cut on the record 34 by the operator

20 pressing his finger against the finger piece 54a carried by the gage-bar until the flat end 51 of the gage-bar comes in contact with the record surface, at which time the edge of the knife will be located forwardly of the record 25 a predetermined amount.

In order to hold the knife-bar 45 in any manually adjusted position, means are provided for locking the knife-bar in the knife-bar carrier 46 so that it will be firmly held

30 while shaving a record. This means, in the form shown in the accompanying drawings, comprises a shaft 55 mounted to rotate in the carrier 46 adapted to extend transversely of the knife-bar 45. The shaft 55 is provided

35 with a cam section 56 adapted to engage a flat surface 57 on the bottom of the knife-bar 45 so that when the shaft 55 is rocked by a spring 58 (Figs. 2, 3) the cam section 56 will be brought into engagement with the flat surface

40 57 on the knife-bar to firmly lock the knife-bar in place. The cam section 56 is so arranged that should the knife-bar 45 under cutting pressure tend to move backwardly it would cause the shaft 55 to be rocked, thereby 45 causing the cam 56 to move tightly and firmly engage the knife-bar and prevent its further movement.

A manually operable release lever 59 which is fastened to the end of the cam shaft 55 is 50 provided to actuate the shaft and release the knife-bar 45. A spring 58 anchored in the housing and to the release lever 59 serves to normally hold the cam section 56 of the shaft in contact with the flat surface 57 of the knife-bar.

The gage-bar is arranged to follow the knife-bar 45 considering the direction of travel of the carriage in shaving a record. Consequently, the knife-bar and gage-bar are 60 adapted to be set to position to take a first cut when the carriage is at the end of its travel (shown in Fig. 1) after finishing a shaving operation.

The first or preliminary cut is seldom sufficient to properly finish the record surface.

For the purpose of taking additional or finishing cuts of predetermined extent without manually resetting the knife-bar 45 in the housing, means are provided for automatically advancing the knife 39 toward the record 34 a predetermined extent incidental to the operation of moving the carriage to starting position of travel. Accordingly, the knife-bar carrier 46 is pivotally mounted on a shaft 60 carried in a pair of ears 61 and 62 formed integral with the carriage 17 and between which ears the end 63 of the knife-bar carrier snugly fits. The shaft 60 is parallel to the axis of the mandrel 24 so that when the knife-carrier 46 is rocked on the shaft, 70 the knife 39 will be moved toward or from the record, according to whether the knife-bar carrier 46 is given a clockwise or counter-clockwise movement, as seen in Fig. 6.

Normally, the knife-bar carrier 46 is urged 75 rearwardly, that is to say, away from the mandrel 24, by means of a spring 64 located in the carriage frame 17 which forces a plunger 65 upwardly against a forwardly extending arm 66, part of the knife-bar carrier 46. It is against the tension of the spring 64 that the knife-bar carrier is advanced step-by-step to move the knife 39 closer to the record 34 for successive finishing cuts.

This step-by-step movement of the knife-bar carrier 46 is controlled by a cam-disc 67 mounted on a stud 68 on the carriage 17, cooperating with a roller 69 mounted on a stud 70 carried by the arm 71 of the cutter-carrier. The spring 64 normally urges the knife-bar carrier 46 rearwardly so that the roller 69 contacts with the periphery of the cam disc.

The cam disc 67 is provided with a series of ratchet teeth 73 adapted to be engaged by a feed pawl 74 pivotally mounted on a pawl-carrier 75 which pivots on a stud 76 carried by the carriage 17. The ratchet teeth 73 are also engaged by a back-check pawl 77 pivotally mounted on the stud 76 and normally urged by the weight of its arm 78 into engagement with the ratchet teeth to prevent return movement of the cam disc 67 by action of a spring 79 located in an undercut portion in the boss 80, see Fig. 6.

In order that the cam disc 67, and hence the knife 39 may be moved step-by-step to accommodate for successive finishing cuts as an incident to the movement of the carriage to position to start shaving a record, the carrier 75 for the feed pawl 74 is arranged to overlie a projection 81 on the base plate 12 when the carriage is, as shown in Figs. 2 or 3, in the position at the end of a shaving operation. The parts are so arranged that when the carriage 17 is raised by means of the hand-piece 18 from the positions shown in Figs. 1 and 6 pivotally on the carriage rod 15, the lower portion of the pawl-carrier 75 engages the projection 81 on the frame. 120 125 130

and causes the pawl 75 to engage a ratchet tooth on the cam disc 67 and move the latter an amount equal to the distance between two teeth, the pawl 75 at this time moving block-wise, as seen in Figs. 2 and 3, against the tension of a spring 82. While the cam disc 67 is being so moved, one of the ratchet teeth thereon passes the back-check pawl 77 and the latter then prevents the return of the cam disc 67 to starting position.

This upward swinging movement of the carriage 17 is necessary to allow movement of the carriage to starting position, for by it the feed-nut 41 is removed from the feed-screw shaft 40, and the knife 39 and gage 49 are moved away from the record. With the carriage so raised, it is moved longitudinally of the machine toward the other or starting end of the record and, upon reaching that end, it is allowed to descend when the feed-nut 41 again engages the rotating feed screw 40 and causes longitudinal travel of the carriage, and the knife again engages the record 34 and shaves the same as a first finishing cut.

During the movement of the carriage to starting position, the feed-pawl carrier 75 slides off the projection 81 and is returned to its normal position by a spring 83 wrapped around the stud 76 and having one end anchored in the pawl carrier 75 while the other end is anchored in the carriage 17.

If the first finishing cut is not sufficient to provide a satisfactory recording surface on the record, additional finishing cuts may be obtained by again raising the carriage 17 and moving it to starting position. Thus, without making any manual readjustments of the knife, the automatic advancing means, comprising the feed pawl 74 and cam disc 67 above referred to, will advance the knife by moving the knife-carrier 46 arcuately toward the record during the raising of the carriage.

After the record has been satisfactorily shaved, the knife 39 and knife-bar carrier 46 with the step-by-step advancing means, comprising the cam disc 67, are returned to normal position so that the knife may later be manually set to take a first or preparatory cut from a new record. To do this, the lever 59 is operated to rotate the cam shaft 55 against the tension of the spring 58 to thus release the knife-bar 45. When so released, the knife bar is restored to inoperative position by means of a spring 84 located in the knife-carrier 46. At the same time, the knife-advancing cam disc 67 is released so as to permit its return by the spring 79 by causing the back-check pawl 77 to be disengaged from the ratchet teeth 73.

This is accomplished without requiring attention on the part of the operator by providing a connection, between the weight

arm 78 of the back-check pawl and an arm on the knife-bar lock lever 59, comprising a lug 85 on the weight arm of the back-check pawl which is adapted to extend into an aperture 86 on the knife-release lever. Hence, when the knife-release lever 59 rotates with the shaft 55, the arm thereon will raise the arm 78 of the back-check pawl lever 77 and remove the pawl from engagement with the ratchet teeth. By this operation, the cam disc 67 is permitted to be returned to normal or initial position by the spring 79, because the feed pawl 74 is normally out of engagement with the ratchet teeth 73. When the cam disc 67 is returned to normal or initial position, it allows the knife-bar carrier 46 to be moved to its normal or initial position by means of the spring 64 provided for the purpose. Movement of the cam disc 67 is limited in both directions by a stop pin 87 engaging shoulders 88 and 89 on the cam disc.

As explained above, means have heretofore been provided for manually releasing the knife-bar locking means for restoring the knife-advancing means and for separately ejecting the record. According to the present invention, however, means are provided for automatically and coordinately releasing the knife-locking means, restoring the knife advancing means, and ejecting the record incidental to the operation of moving the end gate 26 from the mandrel supporting position.

The present invention further provides means comprising an automatic trip-off arrangement to disassociate the record-ejector, knife-advancing means and knife-bar locking means from the end gate when the latter has completed its movement to non-supporting position with respect of the mandrel.

Before continuing with the description of the above, attention is called to the fact that much of the record-ejector shown in the accompanying drawings is similar to the usual record-ejectors for record-resurfacing machines. This usual construction comprises a record-ejector plunger 90 slidable longitudinally of the machine in the standard 91 and normally held in inoperative position by a spring 92. The plunger may be moved forwardly, until a head 93 thereon engages the record to loosen it from the mandrel 24, by movement of a lever 94 mounted on a rocker-shaft 95 journalled in the standards 96 and 97. The rock-shaft 95 is usually provided with a manually operable lever which serves to rotate the rock-shaft and thereby move the lever 94 and related plunger 90 against the record's edge to eject the same.

According to the present invention, however, this manually operable means mounted on the rock-shaft is dispensed with and in-

stead the rockshaft is automatically actuated by means operatively related to the record-supporting end gate 26. This means comprises a cam 98 secured to the stud 27 to which the gate 26 is also secured. This cam 98 cooperates with a bell-crank 99 pivoted on a stud 100 and connected to a link 101 by a stud 102. The link 101 is movable longitudinally of the machine on a stud 103 sliding in an aperture 104 therein and supports a lever 105, which is held thereon by a stud 106, and a spring 107, the purpose of which is hereinafter explained.

In the first part of the movement of the 15 end gate away from the mandrel supporting position (Fig. 2), the link 101 is automatically moved by the cam 98 in the direction of the arrow shown in Fig. 3, and thereby causes the lever 105 to engage a lever 108 fixed to the 20 rockshaft 95 and moves the rockshaft in a counter-clockwise direction, see Fig. 3, causing the ejector lever 94 and plunger 90 to move toward the record until the record is released from the mandrel.

25 This is a very advantageous result for, by it, the time and energy heretofore required for separately manually operating the record ejector is saved and no mental effort is required by the operator relative to the proper 30 sequence of operation for conditioning the machine, since the record is automatically ejected incidental to the regular operation of opening the end gate 26.

It should be especially noted that the present invention also provides automatic trip-off means for the return of the record-ejector to inoperative position when the end-gate is completely opened, thereby permitting the mandrel to receive a new record without interference with the plunger 90. To do this, the lever 105 is made in the form of a trip-lever and has an ear 109 which engages a cam section 110 of the lever 108 when the link 101 has been moved longitudinally as viewed in Fig. 3, a distance sufficient to complete the movement of the ejector plunger. With further movement of the link 101, as the opening movement of the gate continues, the ear 109 in contact with the cam section 110 causes a 40 toe portion 111 of the trip-lever 105 to move over a step 112 on the edge of the lever 108 until the toe 111 slips off the step 112 (as it is about to do as shown in Fig. 3). After this trip-off, the plunger 90, the rock-shaft 95 45 and related parts are moved to inoperative position by the spring 92, irrespective of further movement or lack of movement of the end gate.

With the further movement of the end gate 50 26 to its extreme open position, the link 101 is moved further to the right as shown in Fig. 3 and the ear 109 of the trip lever 105 travels over the cam surface 110 of the lever 108 while this lever is positioned as shown in 55 Fig. 2. With the end gate 26 fully opened

the operator removes the shaved record tablet from the mandrel 24 and then places another tablet thereon for shaving after which the end gate 26 is closed, and during this operation the ear 109 of the trip lever slides upwardly over the cam section 110 of the lever 108 until the toe 111 of the trip lever engages the cam section 113 and rides over the step 112 when it will again be positioned as shown in Fig. 2.

70 Another particularly important feature of the present invention is the provision of automatic means operatively related to the end-gate actuated record-ejector for releasing the knife-locking means and restoring the knife-advancing means, thereby allowing the same to be returned to inoperative position incidental to the operation of moving the end-gate out of mandrel supporting position when the carriage is in predetermined position.

75 According to the present invention, this means comprises a bell crank 114 pivoted on the stud 103 and adapted to be moved clockwise by action of a roll 115 mounted on the rock-shaft lever 108 contacting with an extension 116 of the bell crank which forces the bell crank in a clockwise direction, thereby causing an extension 117 of the bell crank to contact with and vertically raise a spring 80 pressed plunger 118 which is mounted to slide 85 in the frame.

According to the present invention, this means comprises a bell crank 114 pivoted on the stud 103 and adapted to be moved clockwise by action of a roll 115 mounted on the rock-shaft lever 108 contacting with an extension 116 of the bell crank which forces the bell crank in a clockwise direction, thereby causing an extension 117 of the bell crank to contact with and vertically raise a spring 80 pressed plunger 118 which is mounted to slide 85 in the frame.

Further movement of the bell crank 114 with the extension 117 in contact with the plunger 118 forces the same upwardly until it contacts with the stop pawl extension 119, 100 moving the latter clockwise. This clockwise movement of the stop pawl through its connection with the knife-bar release lever 59 in the aperture 86 moves the lever 59 and shaft 55 until the knife-bar 45 is released when it 105 will be returned to inoperative position by the spring 89, and also moves the stop pawl 77 out of engagement with the teeth 73 of the cam disc 67, thereby permitting the knife bar carrier 46 and the knife-advancing means to be 110 returned to normal inoperative position by action of the springs 64 and 79 respectively.

115 It will be noted that the trip-off arrangement for the record-ejector above described also serves to return the release plunger 118 to normal position. This is accomplished after the trip-off occurs when the lever 108 carrying the roll 115 moves in a clockwise direction, thereby permitting the bell crank 114 and plunger 118 to return to normal position 120 by action of the spring 120.

125 Thus, it will be seen that the present invention provides means for accomplishing the advantageous results of coordinately and automatically releasing the knife-locking means, restoring the knife-advancing means, and ejecting the record incidental to the usual and regular operation of opening the mandrel-supporting end-gate, and provides such means with an automatic trip-off for return- 130

ing the record-ejecting mechanism and the knife-bar lock and advancing mechanism restoring means to their normal inoperative positions when the mandrel-supporting end-gate is moved to its completely opened position, thereby conditioning the record-resurfacing machine to receive another record for shaving.

It will also be noted that the present invention provides operating means for releasing a record from its support which means permits the record release or ejector to return to its normal inoperative position after having performed its function of releasing the record from its support.

Variations and modifications may be made within the scope of this invention, and portions of the improvements may be used without others.

Having thus described the invention, what is claimed as new and for which it is desired to obtain Letters-Patent, is:—

1. In a record-resurfacing machine, the combination of a mandrel for supporting a record to be resurfaced; an end-gate; and means operatively related to the end-gate for automatically ejecting a record from said mandrel in response to movement of the end-gate.

2. In a record-resurfacing machine, the combination of a mandrel for supporting a record to be resurfaced; an end-gate; a record engaging tool; means for locking the record engaging tool in desired relationship with the record; and means for automatically and coordinately releasing the tool locking means and ejecting the record incidental to the operation of moving the end-gate out of operative position.

3. In a record-resurfacing machine, the combination of a mandrel for supporting a record to be resurfaced; an end-gate; a record engaging tool; automatic means for advancing the record-engaging tool toward the record for successive cuts; and means for automatically and coordinately restoring the tool advancing means and ejecting the record incidental to the operation of moving the end-gate out of operative position.

4. In a record-resurfacing machine, the combination of a mandrel for supporting a record to be resurfaced; an end-gate; a record engaging tool; means for locking the record engaging tool in desired relationship with the record; automatic means for advancing the record engaging tool toward the record for successive cuts; and means for automatically and coordinately releasing the tool locking means, restoring the automatic tool advancing means, and ejecting the record incidental to the operation of moving the end-gate out of operative position.

5. In a record-resurfacing machine, the combination of a mandrel for supporting a record to be resurfaced; a carriage; a record

engaging tool; an end-gate; means for locking the record engaging tool relative to the record; means for automatically advancing the record-engaging tool a predetermined extent toward the record for successive cuts; a record-ejector; and means operable only when the carriage is in predetermined position for automatically and coordinately releasing the tool locking means, restoring the tool advancing means, and ejecting the record incidental to the operation of moving the end-gate out of operative position.

6. In a record-resurfacing machine, the combination of a record-supporting mandrel; an ejector for the record; and means for operating the ejector comprising mechanism adapted to permit return of the ejector to normal inoperative position after said ejector has been moved by said operating means a predetermined extent in operating direction and before the said operating means has been released.

7. In a record-resurfacing machine, the combination of a record supporting mandrel; an end-gate; a record engaging tool; means for locking the tool relative to the record; an ejector for the record; and means for automatically and coordinately releasing the tool locking means and operating the record ejector incidental to the movement of the end-gate out of operative position, said means being adapted to permit return of the tool locking means and record ejector to normal or inoperative position after said end-gate is moved a predetermined extent.

8. In a record-resurfacing machine, the combination of a mandrel for supporting a record to be resurfaced; an end-gate; a record-engaging tool; tool advancing means; an ejector for the record; and means for automatically and coordinately restoring the tool advancing means and operating the record-ejector incidental to the movement of the end-gate out of operative position, said means being adapted to permit return of the tool advancing means and record ejector to starting position after said end-gate has been moved a predetermined extent.

9. In a record-resurfacing machine, the combination of a mandrel for supporting a record to be resurfaced; an end-gate; a record-engaging tool; means for locking the tool relative to the record; means for advancing the record engaging tool toward the record for successive cuts; an ejector for the record; and means for automatically and coordinately releasing the tool locking means, restoring the tool advancing means and ejecting the record incidental to the movement of the end-gate out of operative position, said means being adapted to permit return of the tool locking means, the tool advancing means, and the record-ejector to normal position after said end-gate is moved a predetermined extent.

10. In combination, a record-support; means for releasing a record from said support; an operating device for said means; and a trip-off connection between said operating device and said means for disconnecting said means from said operating device upon the completion of the operation of said means. 5
11. In combination, a record-support; means for releasing a record from said support; an operating device for said means; a trip-off connection between said operating device and said means for disconnecting said means from said operating device upon the completion of the operation of said means; and means for returning said means to an operative position when disconnected from said operating device. 10
12. In combination, a record-support; a record-ejector; record-ejector operating means; and means to permit return of the record-ejector before the return of the operating means therefor. 20
13. In combination, a frame; a record-supporting mandrel; a record-ejector; a lever on said frame; means to operate the record-ejector when said lever is moved; and means to permit return of the ejector before the return of the lever. 25
14. In combination, a record-supporting mandrel; a record-ejector; an end-gate; and means operated by the said end-gate to operate the record-ejector. 30
15. In combination, a record-supporting mandrel; a record-ejector; an end-gate; means for operating the record-ejector incidental to the movement of the end-gate; and means to permit return of the record-ejector before the return of the end-gate. 35
16. In combination, a frame; a lever on said frame; a record-supporting mandrel; a record-engaging tool; tool-locking means; a record-ejector; means for operating the record-ejector and releasing the tool-locking means incidental to the movement of the lever; and means to permit return of the tool-locking means and the record-ejector to normal position before the return of the lever. 40
17. In combination, a frame; a lever on said frame; a record-supporting mandrel; a record-engaging tool; tool-locking means; tool-advancing means; a record-ejector; means for operating the record-ejector, releasing the tool-locking means and restoring the tool-advancing means incidental to the movement of said lever; and means to permit return of the record-ejector, the tool-locking means and the tool-advancing means to normal position before the return of said lever. 50
18. In combination, a frame; a lever on said frame; a record-supporting mandrel; a record-engaging tool; means for advancing the tool toward the record for successive finishing cuts; a record-ejector; means for operating the record-ejector; release means for restoring the tool-advancing means incidental to the movement of said lever; and means to permit return of the record-ejector and said release means before the return of the lever. 55
19. In combination, a record-supporting mandrel; a record-engaging tool; means to lock said tool; tool-advancing means; a record-ejector; a lever; means for operating the record-ejector and/or release means to restore the tool-advancing means and/or release the tool-advancing means, incidental to the movement of said lever; and/or means to permit return of the record-ejector and/or said release means and/or the tool-locking means to normal position without returning said lever. 60
